Claims priority, application Germany, Sept. 1, 1960,
C 22,259
8 Claims. (Cl. 292—167)

The present invention relates to a latch bolt lock with hollow cylindrical crossing casings one of which contains the latch bolt assembly, and the other drive means which activates the latch bolt assembly.

Rotatable drive sleeves are positioned on the inner and the outer side of the door, and these have door knobs connected to them which are in driving connection with a pivoting arm and an articulated lever member which is connected with the latch bolt.

It has been proposed to facilitate the installation of a lock into a door by using hollow cylindrical casing parts for the latch bolt and its driving means, which casing parts are arranged at right angles to each other. But in such arrangements, the connection of the casing parts with each other in the door was not heretofore sufficiently rigid, and permitted tilting of the inner parts, so that the mechanism used was only adaptable for locks with simple driving means.

The object of the invention is to improve the known mortise locks by the combination of design features which provide thereby a very simple latch bolt lock which can be manufactured at low cost with additional safety and locking devices, and which is versatile and provides troublefree installation into a door.

These and other objects and advantages of this invention will be apparent from the following description and claims.

FIGURE 1 is a horizontal cross section of the latch bolt lock as installed in a door, taken along line I—I of FIGURE 2.

FIGURE 2 shows the lock in section along line II—II of FIGURE 1, with the latch bolt in the extended position.

FIGURE 3 is a view similar to that of FIGURE 2 with the latch bolt shown in the withdrawn release position.

FIGURE 4 is an exploded perspective view of the latch bolt lock.

FIGURE 5 is a perspective view of the hollow cylindrical central casing part for the drive means.

FIGURE 6 is a perspective view of the locking sleeve which engages the casing part of FIGURE 5.

FIGURE 7 is a perspective view of the corresponding escutcheon plate.

FIGURE 8 is a perspective view of the latch bolt lock mechanism.

FIGURE 9 is a horizontal sectional view of a lock assembly similar to that shown in FIGURE 1.

FIGURE 10 is a side view of the push button rod assembly shown in FIGURE 9.

FIGURES 11A to 11C are end views of the push button rod along the line II—II of FIGURE 9, showing three different positions of the mechanism.

In FIGURES 1 to 3, the hollow cylindrical latch bolt casing part is designated by 1, and has integral therewith a flat housing section with opposite lateral walls 3 and 4. This section passes through a hollow cylindrical casing part 5 arranged transversely to it. The cylindrical casing part houses the rotatable drive sleeves 6 and 7.

The latch bolt 8 is guided with an integral cylindrical latch extension section 9 which is telescopically fitted within the hollow cylindrical casing part 1. The latch bolt 8 is spring biased in the outer locking position under

2

the influence of two diametrically opposed helicoidal springs 10.

The springs are guided in recesses 11 within the latch bolt 8, and at their other ends are supported on projections 12.

It is also possible to use a single coil spring which would be telescopically fitted within the cylinder 1 instead of the two separate springs shown.

The latch bolt 8 is connected rigidly with a flat rod 13 on the free end of which a lever 14 is pivoted. The other end of lever 14 is pivotably connected to a pivoting arm 15, which is fastened rigidly to a rotatable shaft 16 supported in the lateral walls 3 and 4 of the reduced section of casing 1.

The shaft 16 is arranged preferably on the longitudinal center line of the latch bolt casing 1, and eccentrically disposed with respect to the longitudinal center line of the cylindrical casing part 5. The shaft 16 is preferably located on the side opposite to the latch bolt 8, and carries on one end a transverse arm 17 for continuous engagement into a longitudinal slot 18 of the inner drive sleeve 6. On its other end, the shaft 16 carries a transverse arm 19 which can be coupled within the cylinder lock 45 supported within the outer drive sleeve 7.

The hollow cylindrical casing part 5 is provided on its two ends with an interior thread 21. The extension sleeves 23 and 24 have an outer thread 22 which engages the interior thread 21. Guide escutcheons 26 and 27 have cylindrical sections 28 which are inserted in opposite ends of the opening 29 of door section 30. Extension sleeves 23 and 24 are inserted through the openings in the escutcheon plates 26 and 27 for threaded engagement with the cylinder member 5. Extension sleeves 23 and 24 have shoulders 25 which are moved into engagement with escutcheon plates 26 and 27 to provide a rigid support for the entire assembly.

When installing the extension sleeves 23 and 24 into the casing part 5, the guide escutcheons 26 and 27 are pressed firmly against the door 30. The drive sleeves 6 and 7 are telescopically held in rotatable engagement with the interior surface of extension sleeves 23 and 24 and rest on their inner ends against the walls 3 and 4 of the casing 1. The other ends of drive sleeves 6 and 7 support door knobs 31 and 32. The drive sleeves are held in axial position by conventionally known devices, such as transverse pins or screws and transverse slots.

Within the drive sleeve 6 adjacent the end of the door knob 31, there is a push button 33 which is both rotatable and shiftable axially. The push button 33 is spring biased in its outer position by a helical compression spring 35 which bears against a transverse wall 34 fixed to the drive sleeve 6. Push button 33 is connected rigidly with a long thin rod 36 which has preferably a flat cross section and extends to an opening 37 of the transverse wall portion 34. The other end section of the rod 36 passes through an opening 38 in the casing wall 3 having the same cross sectional shape as rod 36, there being a slight clearance between the rod and the opening. The rod then passes through an arcuate slot 39 in the pivoting arm 15 of the latch bolt linkage. The rod end bears against flange 40 of a sleeve-like coupling and locking unit 40, 41, 42, and 48 which is pivotally supported on the shaft 16 and biased by spring 52 against the pivoting arm 15.

Push button 33 is secured against independent rotational movement by means of the rod 36 which can only be shifted axially within the stationary casing walls 3 and 4 of the latch bolt casing 1. There will be no rotational movement of the rod 36 when the door knob 31 and the drive sleeve 6 is rotated.

The flange 40 carries an axial parallel coupling and locking pin 42 which can be shifted either with the one end as coupling pin into an opening 43 of the pivoting

arm 15 or with the other end as a locking pin into an opening 44 of the opposite stationary lateral wall 4 of casing 1.

The sleeve 41 also has a transverse arm 48 which is in continuous engagement with the longitudinal slot 57 of the outer drive sleeve 7.

In the exterior drive sleeve 7 and its door knob 32 there is incorporated a cylinder lock 45 as an additional drive means which can be rigidly connected with the transverse arm 19 of the shaft 16 by axially shifting a sleeve-shaped coupling member 47 having an end transverse slot 56 towards the interior of the lock assembly when the key as shown in FIGURE 12 is inserted in cylinder 45. The coupling member 47 is spring biased by spring 46 in the disengaged position.

The coupling rod 36 is provided with locking member 50, the action of which can readily be seen from an inspection of FIGURE 8. When the door knob 31 and the sleeve 6 which is integral with locking plate 34 is rotated it is possible to pass the locking member 50 through the opening 37 in the transverse wall 34 so that the coupling rod 36 can be moved axially inward to press against flange 40 and cause the locking pin 42 to move into the opening 44 of the stationary lateral casing wall 4. This locks sleeve 41, preventing any rotary movement, and thereby also locks outer drive sleeve 7 preventing any rotational movement. Thus the latch bolt 8 can not be withdrawn from its extended position by rotation of drive sleeve 7 and its door knob 32.

However, rotation of the inner door knob 31 is possible under these circumstances, and its rotation will also turn plate 34 which in turn will release the rod 36 from its inner position by permitting the abutment member 50 to fit through the opening 37 in plate 34 so that the spring 35 can push the button 33 and the rod 36 outward. This outward movement of the rod 36 will permit the spring 52 to push the sleeve 41 to the left as viewed in FIGURE 1 thus withdrawing pin 42 from opening 44. Thus, it is possible by merely turning the inner door knob 31, to unlock the previously locked outer door knob by removing pin 42 from opening 44 so that sleeve 41 is freely pivotable when outer drive sleeve 7 is rotated.

With respect to the mounting of the assembly in the door, and referring particularly to FIGURES 4, 5, 6, and 7 taken in conjunction with FIGURE 1, it will be noted that the latch bolt housing 1 is fitted through the hollow cylindrical casing part 5 by slipping walls 3 and 4 which comprise the rear section 2 thereof through the opposed lateral passage opening 55 on the hollow cylindrical member. Additional cut out sections 53 are shown which will permit the pivotable arms 17 and 19 to pass through and into the center section of the hollow cylindrical casing 5. The upper and lower vertical cut out portions 54 permit free pivotal movement of the pivoting member 15 of the latch bolt assembly.

The rearward ends of lateral walls 3 and 4 are provided with protruding point members 51 which are forceably embedded into the surface of transverse bore 29 of door 30 to assist in providing a rigid connection between the latch bolt assembly and the door and to assist in maintaining the assembly and its parts in the correct operational position.

Drive sleeves 6 and 7 extend axially through the cylindrical casing part 5 and abut respectively against lateral walls 3 and 4. The inner drive sleeve 6 as shown in FIGURE 4 has openings in its periphery into which protrusions on plate 34 are fitted, so that this plate will rotate with the inner drive sleeve 6 when that part is rotated, this providing the means for releasing the coupling rod 36 from its inward lock position.

The coupling rod 36 is axially movable through the arcuate opening 39 in the pivotable lever 15, and directly engages flange 40 of the spring-biased shiftable sleeve 41. When the coupling rod 36 is shifted to its outer most position as shown in FIGURE 9, the linking pin 42 car-

ried by flange 40 of the shiftable sleeve 41 is permitted to enter opening 43 of the pivotable lever 15 to provide a direct coupling between the pivotable member 15 and the outer driving sleeve 7 through the rotatably mounted shiftable sleeve 41 which has its outer flange 48 in engagement in slot 57 of the driving sleeve 7. Thus, when the coupling rod 36 and the turn button 33 are in their outward extended position, there is a direct mechanical connection between drive sleeve 7 and pivotable lever 15.

The coupling rod 36 is held in its inward position against the pressure of spring 35 pressing outwardly against the push button 33 by means of an abutment 50 on the coupling rod 36 which engages portion 59 of the plate 34. One modification of plate 34 is shown in FIGURES 4 and 11A, 11B, and 11C. A second modification is shown in FIGURE 8.

The operation of the latch lock is as follows:

The inner door knob 31 is mounted on the inner drive sleeve 6 which is connected to shaft 16 which is integral with the pivotable lever 15 through transverse arm 17. When the inner door knob is turned, transverse arm 17 rotates the shaft 16 thus turning pivotable lever 15 through an arc to withdraw the latch bolt 8. The outer door knob 32 is coupled to the arm 15 through drive sleeve 7 and axially slideable sleeve 41 which is rotatably mounted on shaft 16. As shown in FIGURE 9, the flange 48, which is inserted in slot 57, is rotated with outer drive sleeve 7, thus turning drive sleeve 41 and its flange 40 which carries pin 42. Pin 42 is engaged in opening 43 of the pivotable lever 15, so that when sleeve 41 is rotated about shaft 16, so is pivotable lever 15. It should be noted that this will be effected only when the coupling rod 36 and the push button 33 are in the outer-most position. Outer drive sleeve 7 and door knob 32 are disconnected from the pivotable lever 15 when the push button 33 is pressed inward, as can be seen in FIGURE 1.

In order to move the coupling rod 36 to the right of the transverse section 34, it is necessary to turn the door knob handle so that the section 59 as shown in FIGURE 11C is clear of the abutment 50. FIGURES 11A and 11B which are shown looking toward the transverse wall 34 from the lateral casing wall 3 respectively show the abutment positions with respect to section 59 when the coupling rod 36 is in the inward locking position and the outward unlocked position for the door knob 32.

When the sleeve 41 is axially shifted to the lock position with pin 42 in opening 44 of lateral casing wall 4, it is possible to open the door by means of a key inserted in tumbler cylinder 45. This is possible because turning of inner drive sleeve 6 will release the coupling shaft 36 from locked position when the abutment 50 is cleared of section 59 on transverse wall 34. As can be seen in FIGURES 1 and 9, this is possible by axially moving the cylinder 47 inward so that the slot 56 therein engages the arm 19 of shaft 16. Then rotation of the cylinder 47 when the key as shown in FIGURE 12 is turned, will rotate the inner drive sleeve 6 to clear abutment 50 thereby allowing spring 35 to withdraw coupling rod 36. Due to the action of spring 52, sleeve 41 will move axially inward withdrawing pin 42 from opening 44 and allowing it to engage at its other end opening 43 in a pivotable lever 15. This permits rotation of the door knob 32 and retraction of latch bolt 8 when pivotable lever 15 is moved because of the turning of axially sliding sleeve 41 about shaft 16.

Referring to FIGURES 9 and 12, and in particular to FIGURE 12, it can be seen that it is also possible for the latch bolt to be unlocked by inserting a key from the outside through the lock cylinder 45. The tip of the key, as seen in FIGURE 12, presses the coupling member 47 inward so that its slot 56 engages the lever 19 which is mounted on shaft 16. When the key is turned, the lock cylinder 45 turns coupling member 47 and lever 19 so that shaft 16 through lever 17 turns the inner drive shaft 75 6 to withdraw latch bolt 8.

While the invention has been described in connection with different embodiments thereof, it will be understood that it is capable of further modifications, and this application is intended to cover any variations, uses, or adaptations of the invention following, in general, the principles of the invention and including such departures from the present disclosures as come within known or customary practice in the art to which the invention pertains, and as may be applied to the essential features hereinbefore set forth and fall within the scope of the invention or the limits of the appended claims.

What I claim is:

1. A latch bolt lock assembly, comprising, a latch bolt casing, a latch bolt assembly within said casing, an open-ended cylindrical casing having a transverse opening in its side wall into which a rear section of said latch bolt casing is received, so that both casings are held rigidly with respect to each other, an inner cylindrical drive sleeve rotatably supported within one end of said cylindrical casing, and an outer cylindrical drive sleeve rotatably supported within the other end of said cylindrical casing, both of said drive sleeves having a door knob on the free end thereof, a pivoting arm and connecting linkage connected to said latch bolt, a rotatable shaft which extends through said inner section of said latch bolt casing walls and is rigidly connected to said pivoting arm, said rotatable shaft being connected with said inner drive sleeve by a transverse arm which is integral with said rotatable shaft, a spring-biased coupling and locking assembly rotatably and shiftably mounted on said rotatable shaft and a wall of said latch bolt casing, said coupling and locking assembly being in direct continual contact with said outer drive sleeve, said coupling and locking assembly including first means engageable with said latch bolt casing wall in one position thereof to lock said outer drive sleeve, and in another position thereof having second means to couple both of said drive sleeves, and control means disposed within said inner drive sleeve which engages said coupling and locking assembly for axially shifting said coupling and locking assembly to the locked position.

2. A latch bolt assembly as set forth in claim 1 wherein said rotatable shaft has a transversely directed radial arm integral with each end on the outside of said latch bolt casing walls, one of said radial arms being in continuous direct connection with said inner drive sleeve, said outer drive sleeve having independent rotatable driving means, said independent driving means being adapted to engage the transverse radial arm on the other end of said rotatable drive shaft.

3. A latch bolt lock assembly as set forth in claim 1, wherein said rear section of said latch bolt casing has flat sides, and the periphery of said transverse opening of the cylindrical casing has a flat section which engages said

10
15
20
25
30
35
40

flat sides to provide a rigid connection, and an extension sleeve is rigidly connected to each of said open ends of said cylindrical casing, said extension sleeves providing direct support for said drive sleeves.

4. A latch bolt lock assembly as set forth in claim 1, wherein the inner free end of said rear section of said latch bolt casing extends through said open-end cylindrical casing, and has protrusions thereon which penetrate the wood of a door to provide an additional securing means for the latch bolt lock assembly.

5. A latch bolt lock assembly as set forth in claim 1, wherein said control means includes a spring-loaded push button disposed at the center of the inner door knob which has a coupling rod fixed thereto, said coupling rod being in direct engagement with said coupling and locking assembly.

6. A latch bolt lock assembly as set forth in claim 5, wherein said pivoting arm is provided with an arcuate slot through which said coupling rod may pass, the length of said slot being sufficient to permit full movement of the pivoting arm without interference from the coupling rod.

7. A latch bolt lock assembly as set forth in claim 5, wherein the coupling rod between the said push button and the coupling and locking assembly is held in an inward locking position by a transverse wall which is integral with said inner driving sleeve, said coupling rod extending through an opening in said transverse wall, and having an abutment thereon which will be unable to pass through said opening unless said transverse wall is rotated to register the opening with said abutment.

8. A latch bolt lock assembly as set forth in claim 5 wherein said first and second means comprises a pin extending through a flange which is integral with a sleeve which is mounted on said rotatable shaft.
